US00D688505S

(12) **United States Design Patent**
Smith et al.

(10) **Patent No.:** US D688,505 S
(45) **Date of Patent:** ** Aug. 27, 2013

(54) **CHAIR**

(71) Applicant: **Steelcase Inc.**, Grand Rapids, MI (US)

(72) Inventors: **Bruce M. Smith**, East Grand Rapids, MI (US); **Glen Oliver Low**, Hamburg (DE); **James N. Ludwig**, East Grand Rapids, MI (US); **Robert J. Battey**, Middleville, MI (US); **Gordon Jay Peterson**, Rockford, MI (US)

(73) Assignee: **Steelcase Inc.**, Grand Rapids, MI (US)

(**) Term: **14 Years**

(21) Appl. No.: **29/445,974**

(22) Filed: **Feb. 19, 2013**

(57) **CLAIM**

We claim the ornamental design for the chair, as shown and described.

DESCRIPTION

FIG. 1 is a perspective view of a chair embodying the present invention;

FIG. 2 is a front view of the chair;

FIG. 3 is a first side view of the chair;

FIG. 4 is a second side view of the chair;

FIG. 5 is a rear view of the chair;

FIG. 6 is a top view of the chair; and,

FIG. 7 is a bottom view of the chair.

The dashed lines within the figures are shown for illustrative purposes only and form no part of the claimed invention.
